(57) **CLAIM**

The ornamental design for a light as shown and described.

DESCRIPTION

FIG. 1 is a top perspective view of a first embodiment of a light illustrating our new design in a linear light.

FIG. 2 is a bottom perspective view of the first embodiment.

FIG. 3 is a top view of the first embodiment.

FIG. 4 is a bottom view of the first embodiment.

FIG. 5 is a front view of the first embodiment.

FIG. 6 is a rear view of the first embodiment.

FIG. 7 is a right-side view of the first embodiment.

FIG. 8 is a left-side view of the first embodiment.

FIG. 9 is a top perspective view of a second embodiment of a light illustrating our new design in a pendant light.

FIG. 10 is a bottom perspective view of the second embodiment.

FIG. 11 is a top perspective view of a third embodiment of a light illustrating new design in a sconce; and,

FIG. 12 is a bottom perspective view of the third embodiment.

Portions of the light are shown in broken lines. Portions shown in broken lines form no part of the claimed design. Portions of the light are shown with jagged broken lines which define an indeterminate length. The jagged broken lines form no part of the claimed design.

1 Claim, 10 Drawing Sheets
